UNITED STATES PATENT OFFICE.

ZENAS P. ADAMS, OF LITTLE FALLS, NEW YORK, ASSIGNOR TO D. H. BURRELL & CO., INC., OF LITTLE FALLS, NEW YORK.

PUMP.

Application filed February 17, 1927. Serial No. 163,962.

This invention relates to piston pumps, and particularly to a type useful as a milk pump. More particularly, this invention is in the nature of an improvement upon the type of pump disclosed and claimed in U. S. Patent No. 1,069,894, issued August 12, 1913.

An object of the invention is to provide an improved pump of this type, with which endwise movement of the valve cages or valve units in their bores or pockets will be effectively prevented in a simple and practical manner; with which adjustment can be made to prevent movement of the valve cages or units in a bore; with which the valve cages or units may be quickly and easily removed or inserted; with which the valve cages will not become loosened from endwise movement during use of the pump; and which will be relatively simple and inexpensive.

Various other objects and advantages will be apparent from the following description of an embodiment of the invention, and the novel features will be particularly pointed out hereinafter in connection with the appended claims.

In the accompanying drawings:—

Fig. 1 is a side elevation of a pump constructed in accordance with this invention; Fig. 2 is an elevation of a part of the same, with one of the caps or closures removed in order to show the interior of the pump;

Fig. 3 is a sectional plan of the same, with the section taken approximately along the line 3—3 of Fig. 2;

Fig. 4 is a partial sectional elevation of the same, with the section taken approximately along the angular line 4—4 of Fig. 2; and

Fig. 5 is a similar elevation with one of the valve units removed from its pocket, and one of the end caps of the pump detached.

In the illustrated embodiment of the invention, a pump casing 1 is provided with recesses 2 in its opposite ends, and these recessed ends are connected by a plurality of bores 3, 4 and 5 which extend parallel to one another entirely from end to end of the casing. One of these bores, such as 3, may be larger than the others, and serves as a piston cylinder in which a piston 6, shown by dash lines in Fig. 3, may be reciprocated as heretofore, the piston being operated by a stem 7 passing through a packing gland socket 8 provided in one of the end walls or covers 9 of the casing. The other end of the casing is closed by a cover or cap 10. Suitable gasket

rings 11 may be disposed between the covers 9 and 10 and the end walls of the casing, so as to effectively seal the joints between the covers and the casing. The covers, however, form with the recessed ends of the casing, 60 chambers which are in communication with all of the bores 3, 4 and 5 at the ends of the casing.

The cover 9 may be centered to the casing by one or more studs 12 which extend from the cover along the sides of the casing and slide through apertures 13 in ears 14 of the casing. A bail 15 may be pivoted at its ends by pins 16 to opposite side edges of the cover 9, and extends endwise along the casing and 65 across the other cover 10, as shown in Figs. 1 and 2. A rod or screw 17 may be threaded through the cross arm of the bail and bear at its inner end against the cover 10, as shown in Fig. 2, so as to draw the two covers toward 70 one another and firmly clamp them to opposite ends of the casing. The outer end of the rod 17 may be bent angularly as at 18, so as to provide an operating handle to facilitate rotation of the screw.

A valve unit designated generally at 19 is removably disposed in each valve pocket as shown in Figs. 2, 4 and 6. Each valve unit may include a cage formed by annular rings 20 spaced apart by shouldered studs 21 which extend between and through the rings and are riveted over at the outer projecting ends, so as to confine the rings firmly against the shoulders of the studs, as shown clearly in Fig. 4. Additional shouldered studs 22 extend outwardly from the outer end faces of the rings 20 and also extend through and are riveted against the inner faces of the rings. Valve plates or members 23 may be disposed against the inner end faces of the rings for 90 one type of valve, as shown for the valve unit in the pocket 5 in Fig. 4, or against the outer end faces of the rings for a valve acting in a reverse manner, as shown in the pocket 4 in Fig. 4.

The valve plates or member 23 in the pocket 5 are pressed against the end faces of the rings by a compression spring 24, the ends of the spring being received over studs 25 on the plates or valve members so as to be held against displacement therefrom. The valve plates 23 in pocket 5 will be guided toward and from the rings by the studs 21 and will be yieldingly pressed into closed positions against the rings by the spring 24.

In the valve unit plates 23 in the pocket 4 (Fig. 4) identical valve plates or members 23 may be disposed against the outer end faces of the rings 20, but with their faces reversed, so that the studs 25 instead of projecting toward one another will project away from one another.

The valve members or plates 23 also have studs 26 projecting from the faces thereof opposite the studs 25, and a helical tension spring 27 may be hooked at its ends to the studs 26, and extend between the rings, so as to urge the plates 23 yieldingly toward one another and against the outer faces of the ring. The plates 23 which fit against the outer end faces of the rings are guided toward and from those end faces by the second set of studs 22, so that the valve plates cannot become laterally displaced in such a manner that they will not properly seat against the end faces of the rings. Thus the valve cages formed by the rings 20 and studs 21 and 22 may be made identical in construction, and the valve plates or members 23 disposed against either the inner or outer end faces of the rings in accordance with whether a valve acting in one direction or the other is desired.

Suitable clearance is provided between ends of the studs 22 and the covers 9 and 10, to permit movements of the cover toward the casing ends due to the compression of the gaskets 11 as the covers are drawn against the ends of the casing, and a pair of anchorage studs 28 are secured in or threaded into the ends of the casing at points between the pockets 4 and 5. The outer ends of these studs are threaded for the reception of nuts 29 which are sufficiently wide to overlap the pockets 4 and 5 and engage with the valve cages and confine them within the pockets. Either valve cage may be removed from the casing through either end thereof by merely first removing the nut 29 at that end of the casing, and both valve cages may be securely clamped in the pockets and also against all movement endwise in such pockets by merely tightening the nuts 29. Thus the valve cages are confined in their pockets entirely independently of the covers 9 and 10 of the casing, all danger of leakage due to endwise movement or reciprocation of the valve cages in their pockets is avoided, danger of injury to the stud or covers due to impacts is avoided, and all noise eliminated at all speeds of operation of the pump.

The casing is provided with the usual inlet and outlet connections 30, having passages 30^a leading separately to the pockets 4 and 5 at points intermediate their ends, as in the

prior patent referred to. The operation is the same as in the prior patent referred to, except that the valve cages may be removed or interchanged at will merely by first removing the nuts 29.

65

It will be obvious that various changes in the details which have been herein described and illustrated in order to explain the nature of the invention may be made by those skilled in the art within the principle and scope of the invention as expressed in the appended claims.

70

I claim:

1. In a pump or the like, a casing having a plurality of bores from end to end, one of said bores forming a pump cylinder and another bore a valve pocket, a cover closing each end of the casing and permitting communication between corresponding ends of said bores, said casing having a passage leading to said valve pocket intermediate of its ends, a valve unit disposed in said valve pocket, and means carried by the ends of said casing, engaging with said unit, and confining it within said valve pocket independently of said covers to permit removal of either cover without releasing said unit.

80

2. In a pump or the like, a casing having a plurality of bores from end to end, one of said bores forming a pump cylinder and another bore a valve pocket, a cover closing each end of the casing and permitting communication between corresponding ends of said bores, said casing having a passage leading to said valve pocket intermediate of its ends, a valve unit disposed in said valve pocket, a stud carried by each end of said casing beneath and separate from said covers, and means carried by and adjustable along each of said studs and overlying said valve pocket to confine said unit releasably within its pocket, independently of the covers.

90

3. In a pump or the like, a casing having a plurality of bores extending in a direction endwise therethrough, one bore forming a pump cylinder, two others forming separate valve pockets, a cover for one end of the casing and forming with that end a chamber in communication with said pockets and cylinder, valve units mounted in said pockets and removable therefrom through said one end of the casing, and common means carried by said casing to somewhat overlie both of said bores and adjustable into contact with said valve units to tightly confine them within said pockets independently of the cover, and operable to release said units for removal from the pockets.
